(57) **CLAIM**

The ornamental design for set of bowls, as shown and described.

DESCRIPTION

FIG. 1 is an isometric view for set of bowls showing my new design.

FIG. 2 is a top plan view thereof.

FIG. 3 is a bottom plan view thereof.

FIG. 4 is a rear elevation view thereof.

FIG. 5 is a front elevation view thereof.

FIG. 6 is a right side elevation view thereof.

FIG. 7 is a left side elevation view thereof.

FIG. 8 is a top isometric view of one of the small bowls shown unattached and on an enlarged scale.

FIG. 9 is a bottom isometric view thereof.

FIG. 10 is a rear elevation view thereof.

FIG. 11 is a front elevation view thereof.

FIG. 12 is a left side elevation view thereof.

FIG. 13 is a right side elevation view thereof.

FIG. 14 is a bottom plan view thereof; and,

FIG. 15 is a top plan view thereof.

The broken lines shown in the figure drawings are for illustrative purposes only and form no part of the claimed design.
